HUGH W. COLLENDER, OF NEW YORK, N. Y.

Design No. 4,985, dated June 13, 1871.

DESIGN FOR A PORTABLE STAND FOR A BILLIARD-MARKER.

The Schedule referred to in these Letters Patent and making part of the same.

To all whom it may concern:

Be it known that I, HUGH W. COLLENDER, of New York city, county of New York and State of New York, have invented a new Design for Portable Billiard-Marker Stands; and I do hereby declare that the following is a full and exact description thereof, reference being had to the accompanying drawing making part of this application.

Previous to my invention, portable billiard-marker stands have been made of various designs, and adapted both to hang up against the wall, and to stand or rest on a shelf or mantel-piece. But such stands have always been made of wood, and generally possess little beauty of appearance.

My improvement relates particularly to that kind of stand which is intended and adapted to be placed on a shelf or mantel, and I propose in my new design and configuration of stand to render the apparatus more ornamental in appearance.

In the accompanying drawing I have shown, at

Figures 1 and 2, an elevation or face view and a top view of my new marker-stand; and at

Figures 3 and 4 I have shown one of the metal standards and foot-piece, on an increased scale, (being full size of the casting or pattern.)

In the several figures the same part is designated by the same letter of reference.

A A are the two metallic standards, which sustain the wires or "strings" c c, and which are mounted securely on a marble or other suitable base, B.

The wires c are attached at their ends to the standards A, and are provided with the usual buttons or markers d.

Each of the metal standards A is so designed as to present at a¹ and at a² flat vertical faces, through which holes are bored for the wires c c to pass through, and to afford flat bearing surfaces for the nuts f, that hold the wires tight.

The standards are composed actually of two parts or castings, viz., the upright portion A, and the horizontal portion or foot A³, and suitable lugs or bolts, projecting downward from the bottom of A, pass through A³, and into or through the base B, where they are secured by nuts, and thus the parts are all securely locked together.

The operation and uses of the marker-stand described and shown are, of course, the same as usual.

What I claim as new, and desire to secure by Letters Patent, is—

The shape and design of my new marker-stand, substantially as shown and described.

In testimony whereof I have hereunto set my hand and seal this 11th day of February, 1871.

HUGH W. COLLENDER. [L. s.]
